UNITED STATES PATENT OFFICE.

AMBLER DAVIS, OF PHOENIXVILLE, PENNSYLVANIA.

DESIGN FOR A KNITTED UNDERSHIRT.

SPECIFICATION forming part of Design No. 26,752, dated March 9, 1897.

Application filed September 9, 1896. Serial No. 605,336. Term of patent 7 years.

To all whom it may concern:

Be it known that I, AMBLER DAVIS, a citizen of the United States, and a resident of Phoenixville, Chester county, Pennsylvania, have invented or produced a new and original Design for a Knitted Undershirt, of which the following is a specification.

My design is fully shown in the accompanying drawings, in which—

Figure 1 represents a face view of a knitted undershirt embodying the design; and Fig. 2 is a view on a larger scale, showing more in detail some of the features of the design.

The shape of the undershirt and the finish of the same at the neck are immaterial, my design relating to the front portion of the shirt and consisting of a knitted undershirt, the essential feature of which design is a rectangular breast-panel A, centrally located in said front portion of the shirt and extending

downwardly some distance from the neck, this breast-panel being formed in the fabric composing the shirt by a change in the character of the knitted stitch, as shown in Fig. 2.

Extending from the breast-panel to the bottom of the garment I also form, by preference, a stripe B of the same width as the panel and composed of a number of small parallel stripes *a*, which are continued upwardly through the panel A, as shown in Fig. 1. 25 30

I claim—

The design for a knitted undershirt, substantially as described and shown.

In testimony whereof I have signed my name to this specification in the presence of 35 two subscribing witnesses.

AMBLER DAVIS.
